DESIGN FOR A DISPLAY BOX

Arthur A. Eisenberg, New York, N. Y., assignor to
National Silver Company, New York, N. Y., a
corporation of New York

Application July 30, 1947, Serial No. 140,627

Term of patent 14 years

(Cl. D80—5)

To all whom it may concern:

Be it known that I, Arthur A. Eisenberg, a citizen of the United States, residing in the city, county, and State of New York, have invented a new, original, and ornamental Design for a Display Box, of which the following is a specification, reference being had to the accompanying drawing, forming a part thereof, in which:

Fig. 1 is a plan view of a display box embodying my new design.

Fig. 2 is a side elevation thereof.

The side of the box opposite from that shown in Fig. 2 is the same as that shown in Fig. 2.

The end walls of the cover section of the box are plain, and the end walls of the box, per se, have the same ornamentation as the side walls thereof. The bottom of the box is plain.

I claim:

The ornamental design for a display box, as shown and described.

ARTHUR A. EISENBERG.
